UNITED STATES PATENT OFFICE.

NATHAN CHESLER, OF BROOKLYN, NEW YORK.

SWITCH PLATE.

Application filed February 27, 1925. Serial No. 12,166.

My invention relates to a switch plate adapted to be applied to an opening in a wall or the like and having holes therethrough, to receive a swingable switch element, pushbutton or the like, and the invention more particularly relates to an ornamental switch plate to be employed in substitute of the usual metal plate and produced from a commercial glass sheet.

10 The general object of my invention is to provide a practical form of glass plate adapted to embody the advantages of a metal plate yet not involving an excessive cost in the manufacture and finishing of the glass plate and its appurtenances.

Reference is to be had to the accompanying drawings forming a part of this specification, it being understood that the drawings are merely illustrative of one example of the 20 invention.

Figure 1 is a front view of a switch plate embodying my invention;

Figure 2 is a longitudinal vertical section on line 2—2, Figure 1.

25 In the drawing the letter A indicates a fragment of a wall; a, the opening therein to accommodate the conductor wires, etc.; the letter B indicates a frame bar across the opening a at the front to which bar my improved switch plate 10 is secured, the usual screws C being shown for the purpose, said screws passing through transverse holes 110 in plate 10.

The usual metal plate is provided with a 35 hole in which is positioned the switch element here shown as in the form of a rockable switch arm D. In accordance with my invention a transverse hole 11 is produced in mirror plate by drilling 10 and fitted therein is a bushing 12 which is flanged at the inner side as at 13 and flanged over the outer face of the plate 10 as at 14 to hold the bushing 40 rigidly in position. The handle D projects through the bushing 12. Said bushing protects the glass against liability of chipping and the turned-over front edge of the bushing 45 covers the sharp edge of the glass.

It is the general practice to make flaring the transverse hole in the plate, a function served by which flaring is that a clearance is 50 afforded for locating and conveniently grasping the switch arm in the case of a swingable switch arm or for pressing against a pushbutton where pushbuttons are employed.

55 Forming of a flaring hole in a glass plate cut from a commercial glass plate is attended with considerable expense which constitutes an important item and in order to avoid the making of the hole flaring directly in the glass and at the same time provide flaring walls of the hole, I form the hole 11 in the glass cylindrical but the bushing 12 is cylindrical on the outside to conform to the glass and the inner wall 15 of said bushing 60 is flaring. The mirror 10 constitutes a very ornamental plate and more attractive in many situations than a metal plate. With the addition of the flaring bushing set in a cylindrical hole in said plate, the invention provides a very practical article for its purpose.

65 I would state furthermore that while the illustrated example constitutes a practical embodiment of my invention, I do not limit myself strictly to the exact details herein illustrated, since, manifestly, the same can be considerably varied without departure from the spirit of the invention as defined in the appended claims.

70 Having thus described my invention, I claim:

75 1. A glass switch plate having a cylindrical hole therein, and a bushing in said hole, said bushing flaring at the interior from the inner end to the outer end.

80 2. A glass switch plate having a cylindrical hole therein and having a bushing fitting said hole and having an aperture so shaped as to provide suitable clearance for an oscillating switch handle when projecting therethrough.

NATHAN CHESLER.
